UNITED STATES PATENT OFFICE.

LESTER C. HART, OF CLEVELAND, OHIO, ASSIGNOR TO HI-VOLTAGE EQUIPMENT COMPANY, A CORPORATION OF PENNSYLVANIA.

DISCONNECTING SWITCH.

Application filed April 11, 1924. Serial No. 705,829.

To all whom it may concern:

Be it known that I, LESTER C. HART, a citizen of the United States, and a resident of Cleveland, in the county of Cuyahoga and State of Ohio, have made a new and useful Invention in Improvements in a Disconnecting Switch, of which the following is a specification.

The invention relates to switches, and particularly to those employed in high voltage work for breaking circuits. The invention has for its principal objects; the provision of a switch of the inclined insulator column type having improved means for balancing the swinging column without the use of springs or counterweights for securing the desired balance, thus simplifying the structure and rendering it easy to operate; the provision of an improved arrangement for the connection at the end of the swinging switch arm whereby the requirement for slack in the lead is avoided; and the provision of improved means for making contact between the switch blade and the receiving fingers and for maintaining the blade at an angle such that in closing, the blade will be properly guided into the sleeve hood and have a relatively long sliding engagement with the contact fingers of the switch in such hood. One embodiment of the invention is illustrated in the accompanying drawings wherein:

Figure 1 is a side elevation of the switch. Fig. 2 is a front elevation with the swinging arm in closed position. Fig. 3 is a view similar to that of Fig. 2 with the switch in open position. Fig. 4 is an enlarged detail, perspective view showing the position of the parts at the end of the switch arm when contact is first made. And Fig. 5 is a detail view similar to that of Fig. 4 after the switch is completely closed and with the sleeve hood removed.

Referring to the drawings, 1 is a supporting framework for the switch carrying at its upper end the bracket 2, upon which is mounted the insulator column 3. Mounted for rotation in the lower part of the framework is a shaft 4, provided at one end with the crank arm 5, which carries at its free end the insulator column 6. The axle 4 carries at its other end the crank arm 7, by means of which the axle is turned to operate the switch, this being accomplished by means of suitable connecting rods, and the

arrangement being such that a plurality of switches may, if desired, be arranged in series and operated in unison by means of connections common to all of the switches.

The two insulator columns are similarly inclined upwardly and laterally, and may be of any desired form suitable for high voltage work. The column 6 has secured rigidly to its upper end the switch arm 8 to which the lead 9 is attached, the point 10 of attachment, lying on the extended axis of rotation A of the crank 5, so that there is no lateral movement at this point when the switch arm is swung (Fig. 3), thus avoiding the necessity for providing slack in the lead. The axis A of rotation of the crank also preferably cuts the longitudinal axis of the insulator column 6 about midway between its end, as indicated in Fig. 1, thus balancing the parts carried by the crank 5 with respect to the axis of rotation A, so that the effort necessary to swing the switch arm, is reduced to a minimum, and this is accomplished without the use of counterweights or springs, which would be necessary, in order to secure the desired balance, if the crank 5 were not employed with its axis of rotation located as above pointed out. Ease of operation, without complication, is thus secured.

Secured to the upper end of the switch arm, is the contact blade 11, pivoted to the arm as indicated at 12, and normally held yieldingly at an angle to the switch arm, as indicated in Figs. 3 and 4. This is accomplished by means of a plunger 13, mounted in the casing 14, and normally held in retracted position by a compression spring 15, the plunger having its outer end pivotally connected to the blade by means of the fork 16. The connection 17 transmits current from the switch arm to the blade.

Mounted on the bracket 18 at the upper end of the insulator column 3 is the contact plate 19, and projecting outwardly from the face of the plate are a plurality of pairs of opposing contact fingers 20 and 21, spring mounted and adapted to engage the contact blade, when the switch arm arrives at complete closed position, as indicated in Fig. 5. These fingers are preferably carried by a block or member 22, to which current is supplied from the lead 23. The block is secured to the plate 19 by

any suitable means, such as the screws 28, and is provided with a pair of lugs 24, by means of which the sleet hood 25 is secured in position. The sides of the hood are provided with perforations, through which screws or bolts 26 (Fig. 4), may be passed, and threaded into the perforations in the lugs.

The sleet hood preferably has its lower end of the V-shaped indicated in Fig. 4 so as to act as a guide for the blade 11, and also has a slot 27 in line with the spaces between the contact fingers 20 and 21, in order to permit the entrance of the blade 11 into the hood. When the switch arm is swung outward from the position of Fig. 5 to that of Fig. 4, the spring 15 swings the blade to the inclined position shown, but if, for any reason, the spring should not have sufficient power to accomplish this function, due for example, to an accumulation of sleet or moisture frozen in the joints, the guide slot 27, contacting with the edge of the blade, as it is withdrawn, insures the desired swinging movement of the blade. The spring maintains the blade in angular position so that in closing it will not strike the top of the hood instead of the slot 27. The angular position is further desirable, as in the closing movement the end of the blade first engages the plate 19, and then slides between the fingers eliminating any arcing when the blade first contacts with the fingers, and giving a maximum sliding movement longitudinally of the blade, so that a good contact is secured and the contacting surfaces cleaned and brightened.

What I claim is:

1. In combination in a switch, a pair of similarly inclined insulator columns, one of which is fixed and has contact means at its outer end, a crank, to the free end of which, the inner end of the other column is attached with the extended axis of rotation of the crank cutting such other column intermediate its ends, and a switch arm secured to the outer end of such other column and provided with contact means adapted to contact with the first mentioned contact means.

2. In combination in a switch, a pair of similarly inclined insulator columns, one of which is fixed and has contact means at its outer end, a crank, to the free end of which, the inner end of the other column is attached with the extended axis of rotation of the crank cutting such other column substantially midway between its ends, a switch arm secured to the outer end of such other column and provided with contact means adapted to contact with the first mentioned contact means.

3. In combination in a switch, a pair of similarly inclined insulator columns, one of which is fixed and has contact means at its

outer end, a crank, to the free end of which, the inner end of the other column is attached with the extended axis of rotation of the crank cutting such other column intermediate its ends, and a switch arm secured to the outer end of such other column and having at its outer end contact means adapted to contact with the first mentioned contact means, and having at its other end an extension to which a lead is attached with the point of attachment located in substantial alignment with the axis of rotation of the crank.

4. In combination in a switch, a pair of insulator columns, one above the other, extending upwardly and laterally at similar angles of inclination to the vertical, the upper one of such columns being fixed at its lower end and having contact means at its upper end, a crank arm having an axis of rotation lying in a horizontal plane intermediate the ends of the lower column and having its free end secured to the lower end of such lower column, and a switch arm secured to the upper end of the lower column and provided with contact means adapted to contact with the first mentioned contact means.

5. In combination in a switch, a pair of insulator columns, one above the other, extending upwardly and laterally at similar angles of inclination to the vertical, the upper one of such columns being fixed at its lower end and having contact means at its upper end, a crank arm having an axis of rotation lying in a horizontal plane intermediate the ends of the lower column so that such column is substantially balanced with respect to said axis of rotation and having its free end secured to the lower end of such lower column, and a switch arm secured to the upper end of the lower column and provided with contact means adapted to contact with the first mentioned contact means.

6. The combination with a contact plate having opposing contact fingers upon such face at right angles thereto, of a hood lying over such plate and having at one side, in alignment with the receiving space between the finger, a guide slot, a pivoted switch arm mounted so that its free end swings toward and from said contact plate, a contact blade pivoted to such free end of the switch arm and yieldingly held at an angle to the arm and positioned so that its end contacts with said plate as the end of the switch arm approaches the plate and so that it is guided along the plate, through the guide slot and between the contact fingers bringing such blade into substantial alignment with the switch arm.

7. The combination with a contact plate having opposing contact fingers upon such face at right angles thereto, of a hood lying over such plate and having at one side, in

alignment with the receiving space between the fingers, a guide slot, a pivoted switch arm mounted so that its free end swings toward and from said contact plate, a contact blade pivoted to such free end of the switch arm and yieldingly held at an angle to the arm and positioned so that its end contacts with said plate as the end of the switch arm approaches the plate and so that it is guided 10 along the plate through the guide slot and between the contact fingers bringing such blade into substantial alignment with the switch arm, the said guide slot serving to insure, on the reverse movement of the switch 15 arm, the swinging of the blade about its axis to bring it to an inclined position with respect to the switch arm.

8. The combination with a contact plate having opposing contact fingers upon such 20 face at right angles thereto, of a pivoted

switch arm mounted so that its free end swings toward and from said contact plate, a contact blade pivoted to such free end of the switch arm and yieldingly held at an angle to the arm and positioned so that its 25 end contacts with said plate as the end of the switch arm approaches the plate and so that the blade is forced between the contact fingers and straightened out as the switch arm is brought to complete closed position, 30 and a guide member in advance of said fingers having a slot for receiving the blade and for insuring the swinging of the blade about its axis on the reverse movement of the switch arm. 35

In testimony whereof, I have hereunto subscribed my name this 9th day of April, 1924.

LESTER C. HART.
